UNITED STATES PATENT OFFICE.

BENGT M. W. HANSON, OF HARTFORD, CONNECTICUT, ASSIGNOR TO PRATT & WHITNEY COMPANY, OF NEW YORK, N. Y., A CORPORATION OF NEW JERSEY.

METHOD OF GENERATING FORMERS FOR CONTOUR-GRINDING MACHINES.

1,341,800.

Specification of Letters Patent.

Patented June 1, 1920.

Application filed October 29, 1918. Serial No. 260,210.

To all whom it may concern:

Be it known that I, BENGT M. W. HANSON, a citizen of the United States, residing at Hartford, in the county of Hartford and 5 State of Connecticut, have invented certain new and useful Improvements in Methods of Generating Formers for Contour-Grinding Machines, of which the following is a specification.

10 This invention is particularly adapted for generating formers such as are used with contour grinding machines of the type set forth in my copending application for metal reducing machines, Serial No. 102,458, filed 15 June 8th, 1916, and my copending application for contour grinding machines, Serial No. 247,631, filed July 31st, 1918. Machines of this type require a special former differing from the normal former when they 20 are to be used for grinding cutters having "shovel" teeth; that is, teeth with cutting faces inclined backward and inward with respect to the radii.

The object of this invention is to provide 25 a simple method whereby such special formers can be easily and accurately generated. In the accompanying drawings I have illustrated a grinding machine which is substantially the same as that shown in my 30 aforesaid copending application Serial No. 247,631, in order that my improved method may be fully understood. The grinding machine of itself constitutes no part of the present invention, and it will be understood 35 that the drawings are intended to be merely illustrative and that various changes may be made within the scope of the appended claims without departing from the invention.

40 Of the drawings:

Figure 1 is a plan view of a grinding machine adapted to use a former generated in accordance with this invention and adapted to be used during the generation of the 45 former.

Fig. 2 is an end view of the grinding machine.

Fig. 3 is a plan view of a formed cutter selected for purposes of illustration, it being understood, of course, that the contour

may be varied infinitely in accordance with requirements.

Fig. 4 is an end view of the cutter shown in Fig. 3, the view also showing a grinding wheel in operative relation to the cutter. 55

Fig. 5 is a plan view of a former such as is used for guiding the grinding wheel to grind the teeth of a cutter such as is shown in Fig. 3.

Fig. 6 is an end view similar to Fig. 4 but showing a cutter having undercut or shovel teeth, the effective contour of the cutter being understood to be the same as that of the cutter shown in Fig. 3.

Fig. 7 is an end view, on a greatly enlarged scale, of a fragment of the cutter shown in Fig. 6.

Fig. 8 is a fragmentary face view of one tooth of the cutter shown in Figs. 6 and 7.

Fig. 9 is a diagrammatic view showing the mounting of the former blank.

Figs. 10, 11 and 12 are diagrammatic views showing respectively the successive steps which are followed in the generation of a former in accordance with the invention. 75

Fig. 13 is a diagrammatic view showing another step in the generation.

Fig. 14 is a front view of the preferred form of apparatus adapted for practising the invention, this apparatus being shown as mounted on a grinding machine such as shown in Figs. 1 and 2.

Fig. 15 is a plan view of the apparatus shown in Fig. 14. 85

Fig. 16 is an end view of the apparatus shown in Fig. 14.

In order that my improved method may be clearly understood, I will first briefly describe the grinding machine as shown in Figs. 1 and 2.

1 represents the main frame of the machine which is or may be mounted upon a base or pedestal 2 of any desired construction. The frame 1 is in the form of a hollow 95 box or housing within which is mounted a pantographic mechanism for supporting and controlling the movement of the grinding wheel. This permits the wheel to move horizontally in any direction, but holds it in 100

parallelism while being so moved. Two parallel links 3 and 4 are suitably pivoted at 5 and 6 respectively in the main housing 2 and are pivoted to a cruciform member 7 which 5 is thus mounted for movement forward and backward in parallelism. The cruciform member 7 is provided with two sets of vertical pivots which engage parallel links 8 and 9. These links extend forward through 10 openings in the frame and at their forward ends are pivotally connected with a plate 10. By means of the pantographic connections which have been described the plate 10 is freely movable horizontally in any direction, 15 but is nevertheless always maintained in parallelism. The grinding wheel is carried by the plate 10 by means of devices to be described and is thus bodily movable with respect to the cutter or other part to be 20 ground.

Hinged to the main frame 1 at 11 is a bed plate 12. This plate 12 together with the devices carried thereby can be swung upward about the hinge axis to expose the linkage 25 and other parts contained within the housing 1. To the plate 12 are secured the devices which support the cutter or other part to be ground. For holding the cutter to be ground, or for holding the special fixture 30 embodying the present invention, I provide a hollow work spindle 13 which is rotatable in a bearing 14. If the cutter has a shank this may be inserted directly into the spindle, or if the cutter has no shank it may 35 be mounted on an arbor which may be inserted into the spindle. As illustrated, there is a cutter A mounted on an arbor B. The spindle can be turned by means of a knurled knob 15 and the spindle can be locked in 40 any desired position by means of a clamping screw controlled by a hand lever 16.

In grinding a toothed cutter it is usually necessary to index the cutter in order that the teeth thereof may be successively presented in proper relation to the grinding wheel. To assist in indexing, I preferably provide a stop mechanism adapted to directly engage the front surfaces of the teeth. 45 As illustrated, this mechanism comprises a stop finger 17 carried by a series of rods 18, 19 and 20 which are adjustably connected and which can be secured in any desired relative positions by means of clamping screws. The rod 20 is carried by the bearing 14 and 50 can be clamped by means of the clamping screw 21. It will be seen that by means of these several rods the stop 17 is universally adjustable.

Preferably the bearing 14 is carried by a 60 slide 22 which is movable forward and backward under the control of a screw operated by a hand wheel 23. The slide 22 is mounted on a second slide 24 which is movable transversely on ways carried by the plate 12. For 65 moving the slide 24 there is provided a screw

operated by a hand wheel 25. Preferably I provide an outboard or tailstock bearing 26 which can be used to support the end of the arbor B when such an arbor is used. This bearing is adjustable into alignment with the bearing 14.

Carried by the plate 10 is a grinding wheel supporting bracket 27 which is vertically pivoted to the plate by means of a pivot pin 28. The upper part of the bracket is 75 provided with vertical ways along which is movable a slide 29. This slide is controlled by a screw 30 and a nut 31. The slide can be clamped in adjusted position by means of a nut 32 engaging a suitable screw. The 80 slide 29 is provided with aligned horizontal bearings 33 and 34 in which is mounted a spindle 35. For rotating the spindle there is provided a belt wheel 36. A grinding wheel 37 is mounted on the spindle 35 but is 85 readily detachable so that another wheel can be substituted when required. In order that the bracket 27 may be locked in any desired position of angular adjustment, there is provided a rod 38 pivoted to the plate 10. By 90 means of a bolt 39 the bracket can be frictionally connected to the rod so as to lock the bracket 27 and the associated parts in any desired position.

At the front of the machine are notches 95 adapted to receive projections 40, 40 on a former plate 41 which is used to guide the plate 10 and associated parts as they are moved transversely. The former may be constructed in two sections, as shown in my aforesaid copending application, Serial No. 247,631, but for the sake of simplicity I have herein shown it as constructed in one piece. For securing the former there is provided a clamping plate 42 and a clamping screw 43 100 which extends through a notch 66 in the former. The bracket 27 carries a former stud 44 which is adapted to engage and cooperate with the former 41.

In operation a wheel 37 is selected having 110 a width such that it can enter all of the depressions in the cutter and follow all of the grooves of the contour, and a former stud 44 is selected having the same width as the wheel. For a left-hand cutter such as is 115 shown, the grinding wheel is adjusted vertically so that its axis lies a suitable distance a below the axis of the cutter, this being effected by means of the screw 30 and the nut 31. This adjustment permits the wheel to 120 cut deeper behind the cutting face of each tooth than at the cutting face, thus providing the necessary relief. For a right-hand cutter the wheel is adjusted so that its axis occupies a corresponding position about the 125 axis of the cutter. Initially, the grinding wheel is positioned with its plane of rotation at right angles to the cutter axis and is held in this position by means of the rod 38. The cutter to be ground is put in place 130

in the way shown. A former 41 is selected which corresponds in contour to the contour of the cutter to be ground, and this former is clamped in place by means of the 5 plate 42 and the screw 43. By means of the hand wheel 25 and the slide 24 the cutter is adjusted axially so as to bring it into proper relationship with the former. To bring the cutter and the wheel into operative engagement with each other after the preliminary 10 adjustments have been made, the slide 22 is moved by means of the hand wheel 23.

The operator then moves the wheel longitudinally of the cutter at the same time 15 pressing inward to cause the former stud 44 to follow the contour of the former 41. If necessary, the wheel is moved along the cutter several times until grinding of the tooth is completed. Then the cutter is indexed, 20 use being made of the stop 17 to insure the rotation of the successive teeth to the same position.

Figs. 3 and 5 show the cutter and the former on a somewhat larger scale. The 25 cutter is indicated as having a maximum radius R and a minimum radius R' . Fig. 4 shows, on the same scale, the relationship between the grinding wheel and the cutter. It will be observed that the axis of the wheel 30 is set below the axis of the cutter by a distance a as already pointed out in the description of the grinding machine. The wheel therefore acts upon the cutter at a plane which is parallel to the axis of the 35 wheel but separated therefrom by the distance a . As fully set forth in my copending applications, the wheel is so dressed that its edge has a cross sectional contour which is semicircular in the said plane.

40 Fig. 6 shows the relationship between the grinding wheel and a cutter A' having undercut or shovel teeth. This cutter also has a maximum radius R and a minimum radius R' , the contour being the same as 45 that of the cutter shown in Fig. 3. From this view it will be noted that the axis of the grinding wheel must be set below the axis of the cutter not only through the distance a to provide for the relief but also 50 through a supplemental distance b which corresponds to the distance between the front of a tooth and a plane passing through the cutter axis.

The former shown in Fig. 5, which is used 55 for grinding the cutter shown in Fig. 3, has exactly the same contour as the cutter. However, for grinding the cutter A' shown in Fig. 6, there must be provided a former having a contour slightly different from the 60 normal or effective contour of the cutter. The former to be used for grinding the cutter A' must have a contour which corresponds to the contour of each tooth at the front surface thereof. It will be obvious 65 that this contour will differ slightly from

the effective contour of the cutter when it is observed that the outermost point m of the tooth contour must be swung merely through an angle c to reach the plane of maximum depth of cutting, whereas the innermost 70 point o of the tooth contour must be swung through a greater angle e to reach the said plane of maximum depth of cutting. Of course, a point such as n on the contour at an intermediate distance from the axis must 75 be moved through an intermediate angle such as d . Ordinarily in practice the angle c is 6° , though so far as my invention is concerned, this angle may be varied as desired. 80

As shown on a greatly enlarged scale in Fig. 7, the outermost point m lies at a distance r to the right of the position at which it will effect the deepest cutting; an intermediate point n lies at a somewhat greater 85 distance s to the right of the position at which it will effect the deepest cutting; and the innermost point o lies at a still greater distance t to the right of the position at which it will effect the deepest cutting. 90 From a consideration of Fig. 7 it will be clear that the front contour of each tooth varies from the true effective contour, the amount of variation at any given point depending on the radius at that point. 95

In generating a former to be used in grinding a cutter A' , use is made of a machine such as shown in Figs. 1 and 2 and a former such as 41 is mounted in the usual position in the machine. By means of a 100 suitable fixture, such as will be presently described, a former blank 41' is mounted on the machine in approximately the position which the cutter ordinarily occupies, as shown in Fig. 9. The normal position of 105 the cutter axis is indicated at f . This former blank 41' is preferably preliminarily shaped to conform approximately to the desired contour, and in fact may initially have the same contour as the former 41. 110

Preferably the grinding wheel is set with its axis at the same level as the axis f , the wheel in this case having a semi-circular cross sectional edge contour in a plane passing through the axis, which plane in the 115 present instance constitutes the grinding plane of the wheel.

The blank 41' is mounted with its top surface at a distance from the center f which is the same as the distance between the plane of the front surface of a tooth and the axis of the cutter, this distance being b , as shown in Fig. 6. As shown in Fig. 9, the blank is preferably so adjusted that a perpendicular line erected at its front edge or 120 outermost point m' lies at a distance R from the axis f . Obviously a perpendicular line erected at the innermost point o' of the contour of the blank will lie at a distance R' 125 from the axis f . 130

The former blank having been thus mounted with respect to the axis f , is then swung upward through the angle c , as shown in Fig. 10. The former is then bodily moved with respect to the wheel to a position such that the axis f is at a distance R from the grinding surface, when the former pin 44 is in engagement with the outermost part of the former 41. This upward swinging of the former blank moves the front edge thereof toward the right a distance equal to r , as shown in Fig. 7. The wheel is then passed along the surface of the former blank and all points along the top edge of the blank at a maximum distance from the axis are ground back a distance r . Incidentally, the lower parts of the blank are ground back still farther, but that is immaterial, as will presently appear. Incidentally also, there may be some grinding at points along the top surface of the blank which are at smaller distances from the center, but this also is immaterial.

After grinding is complete, as illustrated in Fig. 10, the blank is inclined to a greater angle such as d as shown in Fig. 11, and the grinding is repeated without adjusting the wheel or changing in any way the position of the axis f . It will be clear that this increased inclination of the blank carries the outermost points thereof above the grinding plane, and these therefore are carried out of the range of action of the grinding wheel. The increased angle, however, permits the wheel to act on intermediate points of the blank such as n'' and to grind them back a distance s from the initial positions.

Then the blank is still further inclined to the angle e , as shown in Fig. 12. This increased inclination carries the parts already ground out of the range of action of the wheel and permits the wheel to have access to the innermost points o'' of the blank and grind them back a distance t . While I have illustrated but three positions of inclination of the former blank during generation, it will be understood that in practice it is preferable to start with the first position, as shown in Fig. 10, and then, by a suitable number of very minute changes, move the blank to the final position shown in Fig. 12, passing the wheel over the blank after each change of position.

The result of the several grinding operations illustrated in Figs. 10 to 12 is that the top surface of the former blank is provided with a contour which is exactly the same as the contour of the front plane of a tooth of the cutter A'. It is to be noted, however, that owing to the relationship between the blank and the wheel, as shown in Figs. 10 to 12, the lower parts of the blank are ground backward so that they do not have the true contour. The thin upper edge of the former resulting from the grinding shown in Figs.

10 to 12 is absolutely accurate in contour and this former could be put in normal position on the machine for grinding a cutter such as A'. It is not well adapted for this purpose, however, as the thin upper edge thereof would become worn after use, thus causing inaccuracies. I therefore prefer to use this former thus generated merely as a master former and to generate from it an operating former having a perpendicular front edge. This is done simply by putting the master former 41' in normal position in the machine and securing a blank 41" in the machine in horizontal position, as shown in Fig. 13. The wheel is passed over this blank 41" using the master former 41' as a guide, and, if necessary, either the wheel or the blank is vertically adjusted from time to time so as to provide a perfectly straight and perpendicular edge at the front of the blank. After the blank 41" has been thus completely ground, it is ready for use in the machine in the usual way for grinding a cutter such as A'.

In Figs. 14, 15 and 16 I have illustrated apparatus which may be used for carrying out the process steps illustrated in Figs. 9 to 13. This comprises an arch frame 45 which is provided with trunnions 46 and 47 adapted respectively to be seated in the bearings 14 and 26. Rotatable on the trunnion 46 is a collar 48 having an arm 49 which is provided with a notch adapted to receive the rod 20 and thus hold the collar against rotative movement. Adjacent the collar 48 is a flange 50 which is rigid with the frame and which is provided with graduation marks to represent angles. Coöperating with these graduations is a mark 51 on the collar 48, and by these means the frame 45 may be adjusted through any desired angle. After adjustment it may be locked by means of the screw 16.

The frame 45 is provided with vertical ways along which is movable a slide 52. This slide is vertically adjustable by means of a screw 53 and a nut 54, and it can be locked in adjusted position by means of a nut 55. At 56 the slide is provided with graduations adapted to coöperate with a mark 57 on the frame. By this means the extent of vertical adjustment of the slide can be determined.

The slide 52 is provided with horizontal ways along which is movable a second slide 58. This second slide 58 can be controlled by means of a screw 59 and a nut 60. The slide 58 is provided with a mark 61 adapted to coöperate with graduations 62 on the slide 52. By these means the extent of horizontal adjustment of the slide can be determined. At the bottom of the slide 58 there is provided a clamping plate 63 and a clamping screw 64 which can be used to hold a former blank such as 41'.

The apparatus which has been described is so constructed and proportioned that the former blank 41' is held in operative relation with the grinding wheel 37, as illustrated. The adjustment of the blank to bring the top surface thereof a distance b below the axis, as shown in Fig. 9, is effected by moving the slide 52 downward through the proper distance, as measured by the scale 56. The former blank is horizontally adjusted to bring the outermost point a distance R from the axis by moving the slide 58, the distance being measured on the scale 62. After these adjustments have been made the former can be inclined to the proper angle by turning the whole frame, the amount of the angle being measured by the graduations on the flange 50.

From the description which has already been given in connection with the diagrammatic views, it will be understood that the former blank, after having been adjusted as described, is first inclined through the angle c and the wheel is then passed over it. Then the angle of inclination is slightly increased and the wheel again passed over the blank. This operation is repeated until the inclination finally reaches the angle e . After this final grinding the master former is complete and is ready to be substituted for the former 41' to be used for generating the operating former, as illustrated in Fig. 13. It will be understood that in generating this operating former the fixture is so adjusted that the former is held horizontal. Relative adjustment during grinding of the operating former to insure a straight perpendicular front edge can be made either by moving the slide 52 upward or downward or by moving the wheel upward or downward.

What I claim is:

1. The herein described method of generating a former for use in grinding a formed milling cutter having teeth with the planes of their front faces separated from the axis, the method consisting in mounting a blank for movement about a pivotal axis in the grinding plane of a grinding wheel, in off-setting the blank from the pivotal axis, in inclining the blank and grinding it by the wheel under the guidance of a former pin and of a former having the same contour as the effective contour of the cutter, and in successively increasing the angle of inclination and repeating the grinding as aforesaid.

2. The herein described method of generating a former for use in grinding a formed milling cutter having teeth with the planes of their front faces separated from the axis by the distance b , the method consisting in mounting a blank for movement

about an axis f in the grinding plane of a grinding wheel, in off-setting the blank from the axis through the distance b , in inclining the blank at the angle c and grinding it by the wheel under the guidance of a former pin and of a former having the same contour as the effective contour of the cutter, and in successively increasing the angle of inclination without changing the relation between the axis f and the former pin and former and repeating the grinding as aforesaid until the angle e is attained.

3. The herein described method of generating a former for use in grinding a formed milling cutter with the maximum radius R and the minimum radius R' and having teeth with the planes of their front faces separated from the axis by the distance b , the method consisting in mounting a blank for movement about an axis f in the grinding plane of a grinding wheel, in off-setting the blank from the axis through the distance b , in inclining the blank at the angle c corresponding to the maximum radius R , in then grinding the blank by the wheel under the guidance of a former pin and of a former having the same contour as the effective contour of the cutter, and in successively increasing the angle of inclination without changing the relation between the axis f and the former pin and former and repeating the grinding as aforesaid until the blank is inclined at the angle e corresponding to the minimum radius R' .

4. The herein described method of generating a former for use in grinding a formed milling cutter having teeth with the planes of their front faces separated from the axis by the distance b , the method consisting in mounting a blank for movement about an axis f in the grinding plane of a grinding wheel, in off-setting the blank from the axis through the distance b , in inclining the blank at the angle c , in then grinding the blank by the wheel under the guidance of a former pin and of a former having the same contour as the effective contour of the cutter, in successively increasing the angle of inclination without changing the relation between the axis f and the former pin and former and repeating the grinding as aforesaid until the angle e is attained, and in using the former thus generated as a master to generate an operating former having its contour surface perpendicular to its parallel outer surfaces.

In testimony whereof, I hereto affix my signature.

BENGT M. W. HANSON.
